INVENTOR

Joseph A. Rogers.

United States Patent Office.

JOSEPH A. ROGERS, OF NEW HAVEN, CONNECTICUT.

Letters Patent No. 101,919, dated April 12, 1870.

IMPROVEMENT IN ARTIFICIAL HORIZON FOR SEXTANTS, &c.

The Schedule referred to in these Letters Patent and making part of the same.

To all whom it may concern:

Be it known that I, JOSEPH A. ROGERS, of New Haven, in the county of New Haven and State of Connecticut, have invented a new and useful Artificial Horizon; and I do hereby declare that the following is a full, clear, and exact description of the construction and operation of the same, reference being had by letters to the annexed drawing making a part of this specification, which is an isometrical representation of the instrument, a central vertical section of the outer part or case having been made, for the purpose of exhibiting the interior parts.

The metallic cylinder A, intersected at right angles in its lower part by the smaller cylinder C D, forms a case which is completely filled with a suitable transparent liquid. For this purpose, almost any liquid may be employed which is quite transparent, and which does not act injuriously on the materials of which the instrument is composed, but I prefer to use glycerine diluted with a small proportion of strong alcohol.

The ends of this case, one of which is shown at B, are made of thin metal, and corrugated to accommodate the varying volume of the inclosed liquid corresponding to different temperatures. One end of the smaller cylinder C D is closed, and the other covered by the plane glass E, care being taken to make a close joint between the glass and metal, so as to prevent the escape of the liquid.

From the closed end C a small tube, F, projects a short distance into the interior of the case, closed at its inner end by the plane glass I, burnished in or otherwise secured, so as to prevent leakage.

At H is an aperture for introducing the liquid which is afterward closed by a screw-plug.

The parts described above are shown in section in the drawing.

A piece, G G, secured to the inside of the case, supports the cross K, which turns on pivots or knife edges about an axis parallel to and a little below the axis of the short tube.

The cross supports the yoke L, which turns on pivots or knife-edges about an axis perpendicular to the axis of motion of the cross, and which axis, when horizontal, intersects the axis of the short tube at right angles. The arrangement of the cross and yoke is such that the latter has a limited motion of rotation in any direction without obstructing the view through the tube.

A hollow float, M, of glass or thin metal, is attached to the yoke which is kept vertical by its buoyancy.

The sight-vane N is also attached to the yoke, one of its edges being straight and parallel to the axis of motion of the yoke, in a direction from that axis at right angles to the direction of the center of the float from the same axis. The distance of the vane from the yoke is made adjustable by proper means. By the

action of the float, the straight edge of the vane is kept constantly in the horizontal plane passing through the axis of motion of the yoke.

A curved spring, Q, attached to the upper part of the case, limits the movement of the float, and prevents the vane from coming in contact with the case.

The sight-vane is viewed through the converging lens O, mounted in the ring P, which slides in or screws into the tube F, to permit adjustment to the position of distinct vision.

A small piece, S, secured within the case, has a straight edge which is seen through the lens parallel to the straight edge of the vane, when the axis of the case is horizontal.

The instrument may be attached to any apparatus with which it is to be used, by means of three lugs, one of which is seen at R.

When the instrument described above is placed so that the axes of the cylindrical parts of the case are horizontal, the straight edge of the sight-vane will be seen through the lens, either with or without a telescope, in the direction of the rational horizon. But if these axes deviate somewhat from the horizontal, the straight edge will still be seen in the same direction, any small displacement of the axis of the lens from the horizontal plane containing the straight edge and the axis of motion of the float being very nearly compensated by the effect of refraction at the surface of the liquid when the sight-vane and lens are placed at proper distances from the axis of motion of the float. These distances depend on the index of refraction of the liquid employed, and the focal length of the lens. They may be determined in any given case by the application of well-established principles of optics, and their adjustment perfected by trial.

When this artificial horizon is attached to a sextant or other instrument held in the hand, the liquid also serves to check the vibrations of the sight-vane, the stability of which is further promoted by making all the parts connected with the float as light as possible.

The parallelism of the vane and the straight edge fixed to the case is at the same time a test of the verticality of the plane of the sextant.

It is not, in general, necessary that the apparent direction of the sight-vane shall be precisely that of the rational horizon since any constant angle between them may be determined by experiment, and afterward applied as index error to all observations made with the same instrument.

Instead, therefore, of placing the sight-vane and center of the float in directions from the axis of motion of the float at right angles to each other, they may be fixed at any convenient angle, the principles of their operation remaining the same.

It may also be desirable in some cases to dispense

with the plane glass I at the inner end of the small tube F. The lens O may then be brought in contact with the liquid inclosed in the case, and fixed at the proper distance from the axis of motion of the float.

What I claim as my invention, and desire to secure by Letters Patent, is—

1. The float M, having a sight vane or its equivalent attached, the whole being so suspended in a transparent liquid inclosed in a suitable case, that the buoyancy of the float tends to bring the sight-vane to rest in some fixed and definite position with reference to the horizon, substantially as and for the purpose described.

2. The construction of the case for containing the transparent liquid and float of an artificial horizon, the same consisting of the intersecting cylinders A and C D, provided with the lens O and transparent plate E, substantially in the manner herein shown and described.

3. The spring Q, in combination with the float M and sight-vane N, arranged to operate substantially as and for the purpose set forth.

JOSEPH A. ROGERS.
